WEIGH CAN AND VALVE MECHANISM

Harry D. Lathrop, Chicago, Ill., assignor to The
Lathrop-Paulson Co., a corporation of Illinois

Application February 1, 1935, Serial No. 4,569

7 Claims. (Cl. 137—21)

This invention relates to weigh can and valve mechanism and more particularly to apparatus adapted for the straining, weighing and discharging of milk.

An object of the invention is to provide improved means for straining, weighing and discharging milk together with automatic means for closing the discharge valve immediately after the flow of milk ceases. Other specific objects 10 and advantages will appear as the specification proceeds.

The invention is illustrated, in a preferred embodiment, by the accompanying drawings, in which—

Figure 1 is a plan view of apparatus embodying my invention; Fig. 2, a view in elevation and part sectional view, the section being taken as indicated at line 2—2 of Fig. 1; Fig. 3, a transverse sectional view of mechanism for raising the 20 valve; Fig. 4, a vertical sectional view, the section being taken as indicated at line 4—4 of Fig. 3; Fig. 5, an enlarged broken detail view of the cushioning device shown in Fig. 4; Fig. 6, an enlarged sectional detail view of the automatic valve closing mechanism; and Fig. 7, a detail plan view of the locking lever shown in Fig. 6.

In the illustration given, A designates a weigh can; B, a dump pan communicating with the weigh can A; C, valve-raising mechanism; and 30 D, automatic valve-closing mechanism.

The weigh can A may be of any suitable construction. In the illustration given, it comprises a cylindrical tank 10 having a frusto conical bottom 11 terminating in a discharge outlet 12. 35 At a point adjacent discharge outlet 12 is a concave recess 13 adapted to receive the lower end of the valve which will be later described. At its top, the weigh can is equipped with a transverse bridge 14 which supports the valve-raising mechanism C. Suitable apparatus (not shown) 40 of well known construction is employed to suspend the can A and to weigh the can and its contents.

The dumping vessel or pan B may be of any 45 suitable construction. In the illustration given, it is radially disposed with respect to can A, and it consists of an outer casing member 15 secured to can A, and an inner or removable sieve member 16 telescopically received within the outer 50 pan 15. The outer pan 15 is provided with a downwardly inclined bottom, and at its front end opens into can A. The inner pan or sieve 16 is provided with a perforated bottom 17 and a perforated front wall 18. The inclination of wall 17 55 is not as great as that of wall 15, thus providing a flow passage for the milk passing through the bottom wall 17 into tank A. The perforated walls 17 and 18 have very minute openings therein but, for the purpose of illustration, such openings are 60 shown in an exaggerated size in the drawings.

The inner pan 16 is provided at its three sides with a marginal flange 19 overlapping the flange 20 of the outer fixed pan 15. On one side, the marginal flange 19 is cut away along the inclined side 21. The inner pan 19 is telescopically received within the outer pan and may be removed for cleaning.

The valve-raising mechanism C, which is rotatably supported upon the cross beam 14, comprises a housing 22 with a shaft 23 journaled 10 therein, the shaft 23 having a handle 24 fixed thereto. Fixed to the shaft 23 on the interior of the casing is a sector arm 24a which is equipped with teeth meshing with the rack 25. The rack 25 is fixed to the valve stem 26. To cushion the fall of the valve stem, I provide a cylindrical tube 27 in which is mounted a plunger 28. The top of plunger 28 is secured to the top of the valve stem 26 by the metal strap 29. It will be observed that both the valve stem 26 and the plunger 28 extend 20 above the casing 22. In the illustration given, plunger 28 is provided with sealing rings 30 of leather or other suitable material and a sealing head 31 which may also be of leather or other suitable material. A clamp 32 secures the head 31 to the bottom of the piston. A trap passage 33, as shown more clearly in Fig. 5, permits the escape of air about the head 31 when the head 25 approaches the bottom of the cylinder. If desired, the cylinder may be provided with minute 30 openings through which the air may escape from the cylinder.

The automatic valve locking mechanism D is shown in detail in Figs. 6 and 7. The bottom portion of the valve stem 26 is preferably in the 35 form of a thin strip equipped with a transverse pin 34. The pin is engaged by a pair of hooks 35 extending on opposite sides of the stem 26. The hook member 35 is secured to the valve 36 by means of a threaded rod 37, the rod 37 being provided with a shoulder at 38 for supporting the 40 valve. The peripheral end portion 39 of valve 36 is adapted to be received within the seat 43 of the discharge portion of weigh can A.

Within the discharge neck 12 is secured a supporting bridge 40 which also provides a central collar guide 41 for the lower portion of rod or stem 37. A tiltable U-shaped frame 42 is supported on pin 43 carried by standards 44, and is adapted to receive the stem 37, as shown more 50 clearly in Fig. 7. The tiltable member 42 is provided at one end with an inclined abutment 45, and at the other end with a perforated cup 46. The perforations or openings 46a within the vessel 55 are large enough to permit liquid received therein to flow rather readily from the cup, but yet small enough to enable the cup to remain substantially filled while milk is being discharged through the discharge opening. On the opposite side of the valve stem from the cup 46 is 60

supported a tilting locking dog 47. The locking member is slotted at 48 to receive pin 49. The upper end of the locking member 47 is provided with a forwardly extending head 50 adapted to 5 engage the inclined abutment 45 of the tilting member 42. The lower portion of the member 47 is turned forwardly at 51 to provide a latch engaging the bottom of the stem 37.

Threadedly engaging bridge 40 is a nut 10 equipped stop-bolt 40^a which may be adjusted to support the member 46 at the desired height.

In the operation of the valve locking mechanism, assuming that the weigh can contains a supply of milk, when the valve stem is raised as 15 by swinging handle 24 in one direction and thereby by swinging sector gear 24 to move rack 25, the milk flows through the opening below valve 36, and into the vessel 46. The filling of vessel 46 causes it to tilt to the position shown in Fig. 6, 20 so that the end 45 abuts the head 50 of dog 47. Thus the lower end or latch 51 of the locking member 47 is forced under the end of stem 37 and supports it in elevated position. As soon as the flow of milk through the discharge opening 25 ceases, the milk within the cup 46 quickly passes out through openings 46^a, and the weighted end 45 of the U-shaped member 42 causes the inner end to swing downwardly below the head 50 of member 47. The latch 51 immediately 30 yields under the weight of stem 37 and the valve 36 drops to its lower position within the annular seat 13. With the construction shown, the operator need only swing the lever arm 24 to elevated position and then release it. The valve will 35 remain open until all of the milk has passed through discharge opening, and then it will automatically close. The automatic closing of the valve immediately upon the discharge of the milk enables the operator to weigh milk more rapidly 40 and with less loss of time, while at the same time permitting him to be engaged in other work while the milk is discharging.

When it is desired to clean the valve mechanism, the valve 36 and coupling 35 may be readily 45 disengaged by raising the latter, and the valve and its stem 37 may be withdrawn from the bearing collar 41. The valve may be placed again in position through a reversal of the steps described.

The inner dump pan 16 with its perforated bottom 50 and front walls enables the milk to be readily strained before it enters the weigh can and, at the same time, is in a convenient position for removal when it is desired to clean the straining surfaces.

55 While in the foregoing description, I have described the specific construction shown in detail, it will be understood that great variation can be made from the details shown without departing from the spirit of my invention. The foregoing 60 detailed description has been given for clearness of understanding only, and no unnecessary limitations should be understood therefrom, but the appended claims should be construed as broadly as permissible, in view of the prior art.

65 I claim:

1. In mechanism of the character set forth, a receptacle, an outlet opening in the bottom thereof, a valve over said opening and adapted to close the same, said valve having a valve stem, means 70 for raising said valve, and means controlled by the flow of liquid through said opening for automatically engaging said stem to lock said valve

in raised position and for automatically disengaging said stem to unlock said valve as soon as the flow ceases.

2. In mechanism of the character set forth, a receptacle, an outlet opening therein, a valve 5 controlling said opening, means for opening said valve, and tiltable means controlled by the flow of liquid through said opening for engaging said valve to maintain it in open position and automatically disengaging said valve to permit it to close as soon as the flow ceases.

3. In mechanism of the character set forth, a receptacle, an outlet opening therein, a valve controlling said opening, means for opening said valve, and tiltable means equipped with a perforated vessel controlled by the flow of liquid through said opening for engaging said valve to lock it in open position, said means serving to automatically disengage said valve to permit it to close as soon as the flow ceases. 20

4. In mechanism of the character set forth, a weigh can, an outlet opening therein, a valve controlling said opening, means for opening said valve, and means controlled by the flow of liquid through said opening for automatically locking said valve in open position until the flow ceases, said last-mentioned means including a locking bar pivoted near its center equipped at one end with a perforated receptacle and a tiltable locking dog arranged to engage said valve at its one end and to engage said locking bar at its other end. 25

5. In combination, a weigh can equipped at its bottom with an outlet opening, a valve controlling said opening, a valve stem connected to said valve and extending upwardly, means supported upon the top of said weigh can for raising said valve stem, a guide bar secured to the bottom of said valve, a guide collar supported by the discharge portion of said weigh can and adapted to receive said guide bar, latch means adapted to engage the bottom of said guide bar when the same is raised to maintain it in raised position, and tiltable means controlled by the flow of liquid through said discharge opening for maintaining said latch bar in latching position as long as liquid flows through said opening, but releasing said latch bar when the liquid ceases to flow. 35

6. In combination with a weigh can equipped at its bottom with an opening, a valve over said opening and adapted to close the same, a valve stem for said valve extending upwardly to the top of said weigh can, means supported by the top of said weigh can for raising said valve stem, and automatic locking means below said valve controlled by the flow of liquid through the discharge opening for maintaining said valve in raised position as long as the liquid continues to flow through said opening, said valve and valve stem being detachably connected. 45

7. In mechanism of the character set forth, a weigh can, an outlet opening therein, a removable valve normally controlling said opening, means for raising said valve to permit liquid to flow through said opening, a removable locking dog for maintaining said valve in raised position, and tiltable means engaging with said locking dog, said tiltable means controlled by the flow of liquid through said outlet. 60
